COMBINED BARBECUE AND SMOKER

Richard B. Johnson, 1310 W. 15th St., Long Beach, Calif.

Filed Aug. 3, 1964, Ser. No. 81,139

Term of patent 14 years

(Cl. D81—10)

FIG. 1

FIG. 2

FIG. 3

I claim:

The ornamental design for a combined barbecue and smoker, substantially as shown.
